Goro R. Tahara, Sunnyvale, Calif., assignor to Philco Corporation, Philadelphia, Pa., a corporation of Delaware

Filed July 2, 1962, Ser. No. 206,598
3 Claims. (Cl. 333—22)

This invention relates to a coaxial transmission line termination and more particularly to a power absorbing load for the termination of high frequency coaxial transmission lines.

High frequency energy is often dissipated in a load to prevent radiation of the energy, the radiant energy being converted to heat energy in the load. Often the load includes an inner conductor comprising an elongated resistor and an outer conductor structure comprising a tapered sleeve surrounding the resistor and connected thereto at one end thereof. The taper of the outer conductor is preferably exponential so that the device exhibits a pure ohmic characteristic. Cooling of such loads is difficult due to the fact that heat producing resistor is surrounded by the outer conductor structure. Numerous schemes have been proposed for cooling such loads, which schemes generally increase in size and complexity as the amount of energy to be dissipated increases.

In U.S. Patent 2,901,710 to E. Garthwaite there is shown a load device which includes an elongated resistor as the inner conductor and a pair of convergent plates disposed at opposite sides of the resistor as the outer conductor structure. The convergent ends of the plates are connected to one end of the resistor and means are provided for applying high frequency energy to be dissipated between the other end of the resistor and the divergent ends of the plates. The plates are vertically positioned for excellent natural convection cooling of the load. For good matching of the load to the transmission line from the source of energy, the plates are substantially exponentially curved. With an exponential curvature of the plates, however, the plates are closely positioned to the resistor at the rear end of the termination whereby arcing may occur.

The principal object of the present invention is to overcome this objection by a simple configuration of outer conductor plates without adversely affecting the matching of the load to the line.

This and other objects and advantages of the invention are achieved by the provision of a slab line coaxial termination having an outer conductor structure which includes a pair of generally vertically positioned convergent plates, which plates are curved inwardly at the upper and lower edges along a portion of the length thereof adjacent the rear or convergent ends. The capacitance between the resistor positioned between the plates and the curved sections of the plates is increased whereby an increased spacing therebetween is permitted without disruption of the impedance matching along the length of the termination. The increased spacing decreases the possibility of arcing between the inner and outer conductor structures.

The invention may be fully understood from the following detailed description of the accompanying drawings. In the drawings, wherein like reference characters refer to the same parts in the several views:

FIGURE 1 is a diagrammatic top view of a termination embodying this invention;

FIGURE 2 is a side elevational view of the termination shown in FIGURE 1, with parts shown broken away for clarity;

FIGURE 3 is a longitudinal cross-sectional view taken on line 3—3 of FIGURE 1;

2

FIGURE 4 is a cross-sectional view taken on line 4—4 of FIGURE 2, and

FIGURE 5 is a development of the end portion of one of the outer conductors of the termination shown in FIGURES 1 and 2.

Reference is first made to FIGURES 1 through 3 of the drawings wherein the termination of my invention is shown comprising an elongated tubular film-type load resistor 10 disposed between a pair of convergent plates 11 of identical construction but designated 11 and 11' for purposes of identification. Except for the inwardly curved end portions of the plates 11 and 11' which will be discussed infra, the plates are substantially plane so as to form a slab or strip line structure. The convergent ends 15 of the plates 11 and 11' are connected to the rear end of the resistor 10 by means of a clamp 12. The resistor 10 comprises the inner conductor of the load and the plates 11 and 11' comprise the outer conductor structure thereof.

20 The divergent front ends of the plates 11 and 11' are secured by screw fastening means 13 to the vertical side walls of a front end connector body 14. A radially directed flange 16 is formed on the connector body 14 by means of which the termination may be mounted on a 25 suitable supporting structure such as a housing or casing, not shown. A line connector member 17 threadedly engages a tapped through hole formed in the connector body, and together with the connector body provides an electrical connection between an attaching collar of a coaxial line, not shown, and the outer conductor structure 30 11, 11' of the termination. A tapered inner connector 18 is coaxially disposed with respect to the member 17 and is electrically insulated therefrom. The inner connector 18 is conductively coupled to the front, or forward, end 35 of the elongated resistor 10 and provides an electrical connection between an inner conductor of a coaxial line (not shown) attached thereto and the inner conductor 10.

As best seen in FIGURE 3, the tubular film-type load resistor 10 may comprise a glazed cylindrical ceramic tube 24, with a resistive film 26 disposed on the external surface thereof. Said film may comprise an alloy including a highly stable tin oxide which is deposited on the external surface of the said glazed ceramic tube, which is then fired at a high temperature to disperse the resistive film throughout the body of the glaze. Bands 28 and 28' of conductive metal such as silver, are applied to the ends of the resistor and extend over the resistance film in good electrical contact therewith. It will here be understood that for purposes of illustration and clarity the showing of the resistance film 26 and conductive bands 28 and 28' are greatly exaggerated dimensionally in the drawing.

55 A generally cylindrical brass pin 29 conductively connects the tapered inner connector 18 to the forward end of the load resistor 10. Pin 29 is formed with integral axial flanges 31 and 32 at the opposite ends thereof. Flange 31 extends over the silver band 28 and is secured thereto by soldering or other suitable means, not shown. The flange 32 extends over the inner free end of the connector 18 for good electrical connection therewith. A dielectric bushing 33 is positioned in the space between the pin 29 and connector body 14. O rings 34 and 36 positioned in grooves in the bushing provide fluid tight seals between the bushing and the connector body 14 and pin 29, respectively.

60 The flange 16 formed on the connector body 14 is provided with holes 38 through which mounting bolts may extend for securing the termination to a suitable support or casing, not shown. As is well understood by those skilled in this art, terminations are commonly supported in casings containing a liquid dielectric such as transformer or mineral oil. With the outer conductor plates in a

generally vertical position, the dielectric fluid easily circulates by convection past the load resistor for cooling thereof. A flow of fluid through the tubular resistor is made possible by radial holes 39 formed in the flange 31 of the pin 29.

The outer conductor plates 11, 11' are maintained a spaced distance apart by dielectric spacers 21 made of polytetrafluoroethylene or the like, secured to the plates by screw fastening means 22. For good matching of the termination to a coaxial transmission line the curvature of the vertical outer conductor plates is substantially at an exponential rate. If, however, the exponential curvature extended to the rear end of the plates, it will be apparent that the plates would be closely positioned to the resistor thereat whereby arcing between the inner and outer conductors may occur. To prevent arcing, or to minimize the possibility of arcing, the rear end of the plates are altered in the manner of this invention (as shown in the drawings and described herein below) to provide a greater spacing between the plates and resistor at the rear end of the termination than is provided in prior art instructions, without an increased reactive effect manifested at the input to the load and without an increased voltage standing wave ratio thereat.

In accordance with my invention a novel outer conductor structure is provided which both minimizes the voltage standing wave ratio in the line to the termination and provides for an increased spacing between the inner resistor and outer conductor structure. As best seen in FIGURE 4, each of the rear end portions 41 and 41' of the plates 11 and 11' are inwardly curved to partially surround the resistor 10. As seen in FIGURES 1 and 4, the facing upper and lower edges of the inwardly curved portions 41 and 41' do not meet but form continuous upper and lower gaps which permit an unimpeded thermosiphonic flow of cooling fluid over all portions of inner resistive rod 10 and which preserve the integrity of the slab line structure 11-11'. The rear end portions 41 and 41' are also of a reduced height and are tapered toward the rear end of the termination. The upper and lower edges of the reduced height end are curved inwardly to form the illustrated rear end portions 41 and 41'. Reference is made to FIGURE 5 of the drawings wherein a development of the end section 41 of one of the plates 11 is shown. Notches 42, 42 directed toward the center of the plate are formed between the main vertical portion of the plate and the rear end portion 41, while similar notches 43, 43 are formed between the rear end portion 41 and connector end 44 to facilitate the curving of the plates therebetween. Holes 46 are formed in the portions 41 and 41' for increased circulation of fluid past the resistor.

By curving the outer conductor plates inwardly at the rear end thereof in the illustrated manner the capacitance between the inner and outer conductor structure is increased thereat whereby an increased spacing between the

curved section of the plates and the resistor may be employed for the proper impedance matching along this length of the termination. With an increased spacing, the possibility of arcing is reduced.

5 My invention now having been described in detail in accordance with the requirements of the patent statutes, various changes and modifications will suggest themselves to those skilled in this art, and it is intended that such changes and modifications shall fall within the spirit and scope of the invention as recited in the following claims.

I claim:

1. A microwave energy dissipating apparatus including an inner conductor comprising an elongated resistor, an outer conductor structure comprising a pair of continuous, convergent plates disposed at opposite sides of the resistor, means connecting the convergent ends of the plates to one end of the resistor, said plates being substantially plane so as to form a slab line structure, the edge portions of said plates adjacent said convergent ends being inwardly curved so that the edges of one of said end portions face the corresponding edges of the other of said end portions, said facing edges being spaced from each other to form two continuous gaps between corresponding edges of each of said end portions.

25 2. A microwave energy dissipating apparatus comprising an outer conductor structure comprising a pair of generally vertically positioned convergent plates, an elongated resistor positioned between the plates and connected at one end thereof to the convergent ends of the plates, an input conductor connected to the divergent ends of the plates and to the other end of the resistor for connection of the apparatus to a source of microwave energy, said plates being substantially plane so as to form a slab line structure, the upper and lower edges of the convergent 30 end portions of said plates being curved inwardly so that said edges face each other, said facing edges being spaced from each other to form continuous upper and lower gaps between corresponding edges of said end portions to accommodate an unimpeded thermosiphonic flow of cooling fluid over all portions of said elongated resistor.

35 3. The invention as recited in claim 2 wherein said inwardly curved end portions of said plates have vertical holes therethrough to accommodate an additional flow of cooling fluid.
